Attorneys

UNITED STATES PATENT OFFICE.

SAMUEL V. REEVES, OF HADDONFIELD, NEW JERSEY.

STOVE.

Application filed July 7, 1925. Serial No. 41,931.

The object of this invention is to devise a novel stove wherein novel means are provided for adjusting the location of a fire so that the fire contact will be restricted to heating the walls of one fire pot, or will heat to a desired degree at the same time the walls of another fire pot, said fire pots, if desired, being water jacketed.

With the above and other objects in view 10 which will hereinafter appear, my invention comprehends a novel stove wherein novel means are provided to adjust a fire so that the fire contact of a fire with two independent surfaces to be heated may be restricted to one surface or may co-operate in a desired relation with two independent or separate surfaces to be heated.

My invention further comprehends a novel hot water stove having two independent 20 water heating systems, and novel means for adjusting the location of a fire to cause it to heat one or both of said hot water heating systems.

It further comprehends a novel hot water 25 stove having a plurality of superimposed water jacketed fire pots, forming parts of independent hot water heating systems and having a source of heat for each fire pot, with means for relatively adjusting the 30 sources of heat, and with means for simultaneously shaking the grates of the sources of heat.

It further comprehends other novel features of construction and advantage which 35 will hereinafter more clearly appear in the detailed description and the appended claims.

For the purpose of illustrating the invention, I have shown in the accompanying 40 drawings typical embodiment of it, which in practice, will give reliable and satisfactory results.

It is, however, to be understood that this embodiment is typical only and that the 45 various instrumentalities of which my invention consists can be variously arranged and organized, and that the invention is not, therefore, limited to the precise arrangement and organization of these instrumentalities 50 as herein set forth.

Figure 1 is a sectional elevation of a stove.

Figure 2 is a section on line 2—2 of Figure 1.

Figure 3 is a section on line 3—3 of Figure 1.

Figure 4 is an elevation showing the upper grate support.

Similar numerals of reference indicate corresponding parts.

Referring to the drawings.

1 designates a stove embodying my invention, and which, for the purpose of illustration, I have shown as a hot water stove.

The general construction of the stove may 65 vary widely in practice but preferably conforms to that shown in my pending application Serial No. 732,623.

The stove as illustrated has a base 2 on which is mounted a base top or ash pit ring 3 which is flanged at its top to receive a pre-heater 4. This preheater 4 is in the form 70 of a ring shaped casting having a water chamber 5 to which cool or cold water is admitted by a conduit 6 leading from a boiler (not shown).

The preheater is recessed at its upper end to receive the cored or water jacketed fire pot 7, the water chamber 8 of which is preferably of greatest diameter intermediate its 75 ends.

The fire pot 7 carries at its upper end a draft ring 9 having at its bottom an outwardly extending flange. The draft ring 9 is provided with a desired number of air inlet holes 10 which are controlled by a slide 80 ring 11 having a grasping handle of any desired construction.

An upper cored or water jacket fire pot 12 has a water chamber 13 the lower portion 90 of which is connected by a conduit 14 with the upper portion of the water chamber 5 of the preheater.

The lower water jacket 7 is provided with a hot water discharge pipe 15, and the upper fire pot 12 is provided with a hot water discharge pipe 16. The lower fire pot 95 is provided with an inlet pipe 17. The top 18 is supported on the upper fire pot and has a removable lid 19 covering the opening through which the fuel is introduced into the stove. The top 18 has a chamber leading 100 to the damper controlled exit flue 20.

The bottom grate 21 is of any desired or conventional construction, is supported on a grate rest 22, and has an extension 23 which 105 is apertured to receive a shaking bar or lever

of the usual construction. 24 designates a support for the upper grate 25. The support 24 as illustrated consists of a base 26 consisting of sides 27 having depending lugs 28, the sides being connected by a cross bar 29 having an opening to receive a bar 30 which is fixed in position by means of a fastening device 31. A bar 32 is adjustably connected with the bar 30 by means of fastening devices 33 which pass through registering apertures 34 in the two bars.

In the position shown in Figures 1 and 4, the upper grate is in what may be called its neutral position, that is, it will only heat the upper fire pot. If the bar 32 is lowered one hole, there will be a one inch fire contact with the upper portion of the wall of the lower fire pot. I provide a plurality of adjustable positions for the upper grate and have indicated in Figure 4 on the bar 30 the positions of adjustment for a one, two, three or four inch fire contact with the lower fire pot 7.

The bar 32 has pivoted to it at its upper end, as at 35, a stud 36 having a polygonal contour at its upper end to adapt it to enter a polygonally shaped recess 37 in the upper grate 25. The bar 32 has fixed to it one end of a spring 38 the free end of which bears against the stud 36 to retain the upper grate 25 in a horizontal position.

The operation of my novel stove is as follows:—

In the winter time a fire is built on the lower grate 21 and the lower fire serves as a source of heat for the lower fire pot and also the preheater 4 and the upper fire pot 12 with which it communicates.

The upper fire pot 12 and the preheater 4 form the hot water supply for household purposes, such as the hot water supply for the bath-room and for the kitchen. The fire pot 7 forms a source of hot water supply for the radiators, so that two independent hot water heaters are provided in the same stove. In the summer when the radiators are not in use, the support 24 is inserted in place so that the lugs 28 extend between the grate bars of the lower grate 21, and the bars 30 and 32 are relatively adjusted, so that the upper grate 25 is positioned so that it will only heat the upper fire pot 21.

In the spring and fall, when it is desired to have a little heat in the radiators but not enough to make it necessary to build a fire on the lower grate, the bars 30 and 32 are adjusted so as to lower the upper grate into such position that the fire on the upper grate will have a direct fire contact with the upper wall of the lower fire pot 7. For example, when the parts are adjusted for the zero aperture, the lower grate is in its neutral position so that it will only heat the upper fire pot 12. I have illustrated four adjustments so that by lowering the bar 32 either a one, two, three or four inch fire contact can

be obtained with the walls of the fire pot 7 and still a sufficient hot water supply will be obtained from the fire pot 12 for household purposes, such as, for example, the kitchen and the bath.

When it is desired to dump the upper grate 25, the cover 19 is removed, and a poker is inserted to rock the grate 25, so that the ashes and fire will drop to the lower grate.

It will be apparent that the upper fire has an independent source of draft, controlled by the slide ring 11; or when lowered below this ring, the usual draft for the lower grate 21 is employed to provide the draft for primary combustion. When it is desired to shake the upper grate all that it is necessary to do is to shake the lower grate 21 by the handle 23, and, since the support is interlocked with the lower grate, the upper grate will be moved in unison therewith.

My present invention has been found in practice to give advantageous and reliable results, since a multiple heating system is provided wherein an unskilled person can relatively adjust the support 24 so that the upper fire can have a desired fire contact with the walls of the lower fire pot, so that whenever desired, the radiator hot water system as well as the household system for hot water can be heated from the same upper fire.

Having thus described my invention, what I claim as new and desire to secure by Letters Patent, is:—

1. In a stove, superimposed fire pots each forming an independent source of heat, an upper fire to heat the upper of said fire pots, an independent source of draft for said upper fire opening through the side walls of the stove between said fire pots, and means to adjust the location of said upper fire to cause it to have a desired fire contact with the lower of said fire pots.

2. In a stove, superimposed jacketed fire pots providing a separate supply of hot water for separate heating systems, each of said fire pots having a cold water inlet and a hot water outlet, a source of heat for the upper of said fire pots, and means to adjust the position of said source of heat to cause it to have a fire contact with the walls of each fire pot.

3. In a stove, upper and lower fire pots each of said fire pots forming an independent source of heat, an upper grate for the upper fire pot, an independent source of draft for said upper grate opening through the side wall of the stove, a lower grate for the lower fire pot, a support for said upper grate, and means to vary the effective length of said support to cause a fire on the upper grate to have a desired fire contact with the lower fire pot and at the same time heat said upper fire pot.

4. In a stove upper and lower fire pots, an

- upper grate for said upper fire pot, an independent source of draft for said upper grate opening through the side wall of the stove, a lower grate for said lower fire pot, a longitudinally adjustable grate support carried by said lower grate and movable in unison therewith and carrying said upper grate.
5. In a stove upper and lower fire pots, an upper grate for said upper fire pot, an independent source of draft for said upper grate opening through the side wall of the stove, a lower grate for said lower fire pot, a longitudinally adjustable grate support carried by said lower grate and movable in unison therewith on which said upper grate is pivotally supported.
10. In a stove upper and lower fire pots, an upper grate for said upper fire pot, an independent source of draft for said upper grate opening through the side wall of the stove, a lower grate for said lower fire pot, a longitudinally adjustable grate support carried by said lower grate and movable in unison therewith on which said upper grate is pivotally supported and means to retain said upper grate in a normally horizontal position.
15. In a stove, a base, a lower grate thereon, a water ring above said grate, a lower water jacketed fire pot above said water ring, an upper water jacketed fire pot above said lower water jacketed fire pot, said water ring communicating with said upper water jacketed fire pot, an upper grate supported on said lower grate, and means to adjust the position of said upper grate so that it will have a fire contact with only the walls of said upper water jacketed fire pot or so that it will as well have a desired fire contact with the walls of said lower water jacketed fire pot.
20. In a stove, a base, a lower grate thereon, a water ring above said grate, a lower water jacketed fire pot above said water ring, an upper water jacketed fire pot above said lower water jacketed fire pot, an upper grate supported on said lower grate, and means to adjust the position of said upper grate so that it will have a fire contact with only the walls of said upper water jacketed fire pot or so that it will as well have a desired fire contact with the walls of said lower water jacketed fire pot, and an independent source of draft for each grate.
25. In a stove upper and lower fire pots, an upper grate for said upper fire pot, an independent source of draft for said upper grate opening through the side wall of the stove, a lower grate for said lower fire pot, a longitudinally adjustable grate support carried by said lower grate and movable in unison therewith on which said upper grate is pivotally supported.

7. In a stove, a base, a lower grate thereon,

SAMUEL V. REEVES.
